UNITED STATES PATENT OFFICE.

WILLIAM J. LUTTON, OF PATERSON, NEW JERSEY, ASSIGNOR OF ONE-HALF TO
MAURICE FRANCK, OF PATERSON, NEW JERSEY.

LOOM.

Application filed December 17, 1924. Serial No. 756,441.

To all whom it may concern:

Be it known that I, WILLIAM J. LUTTON, a citizen of the United States, and resident of Paterson, in the county of Passaic and State of New Jersey, have invented a new and useful Improvement in Looms, of which the following is a specification.

This invention relates to an improvement in looms, in which plaits of any desired width may be woven at predetermined distances apart into a fabric during the continuous weaving thereof.

My invention further consists in providing mechanism for producing the above results which will be very simple, effective and which will not interfere in the regular action of the heddles and lay beam of the loom.

My present invention more particularly contemplates certain improvements in looms of the type shown, described and claimed in my United States Patent No. 628,206, with the object in view of improving the means for controlling the movement of the woven fabric on the winding beam.

A practical embodiment of my invention is represented in the accompanying drawings, in which—

Fig. 1 represents a front elevation of a loom having my improvements applied thereto.

Fig. 2 represents a side elevation of the loom, certain parts being broken away to show other parts more clearly.

Fig. 3 represents a vertical section taken in the plane of the line III—III of Fig. 1, looking in the direction of the arrows.

Fig. 4 represents a detail vertical section of the winding means and adjacent mechanism for the woven fabric, and

Fig. 5 represents diagrammatically four detail views of the fabric, showing the several stages during the weaving of the plait therein.

The main frame of the loom is denoted by 1, the lay beam by 2, the drive shaft by 3, its crank by 4 and the pitman by 5, which pitman connects the crank with the lay beam 2.

To illustrate the operation of my invention I have shown four heddles denoted by 6, 7, 8 and 9, which heddles are mounted in the main frame 1 of the loom and the movements of the same are controlled by rolls and tubes (not shown) on the pattern chain

and intermediate mechanisms, in a well known or approved manner.

The heddles 6, 7, 8 and 9 are all utilized for weaving the ground or body of the fabric, while the heddles 6 and 7 alone are used for weaving the loops which are to form the plaits. When the heddles 6 and 7 are being actuated to form the loops the heddles 8 and 9 remain stationary.

An auxiliary frame 10 is attached to the rear of the main frame 1 and arranged to receive the journals of warp beams 11 and 12. These warp beams 11 and 12 supply the warp threads to the several heddles. The warp beam 11 is provided with the usual weighted frictional device, which consists of a flexible strip 13 passing over a pulley 14 on the warp beam and provided at its dependent ends with a large weight 15 and a smaller weight 16. The function of the weight 15 is to wind the warp threads onto the beam 11, thereby tending to exert the tension on the thread leading to the heddles 8 and 9 rearwardly. The warp beam 12 is also provided with a frictional device which comprises a flexible connection 17 arranged to connect a pulley 18 on the beam and having one end secured to the floor at 19, while the other end has secured thereto a weight 20. The threads from the warp beam 11 are directed over a guide roller 21 mounted in brackets 22 carried by the auxiliary frame 10.

The winding beam 23 upon which the woven fabric is wound is mounted to rotate in supports 24, 25 secured between the breast beam 26 and a girt 27, which breast beam and girt are fixed in the main frame 1. An intermediate winding roll 28, also carried by the supports 24 and 25, is provided with a friction surface for engaging the fabric and preventing it from slipping thereon as the fabric is wound or unwound. Idler rollers 29, 30 are mounted in the supports 24, 25 in close proximity to the winding roll 28 so as to cause the fabric to engage a considerable portion of the periphery of the roll. A train of gear wheels connects the winding roll 28 with the winding beam 23, which train consists of a spur gear 31 carried by the roll 28, a pinion 32 meshing therewith and having a spur gear 33 attached thereto, which spur gear meshes with a pinion 34 fast on the winding beam 23.

The pinion 32 and spur gear 33 are loosely mounted on a stud 35 fixed to the support 25.

Rotary movement is imparted to the winding beam 23 and winding roll 28 in a direction to wind the finished fabric by means of a ratchet wheel 36 mounted on a stud 37 and provided with a pinion 38 which meshes with the spur gear 33. A pawl 39 is arranged to engage the ratchet wheel 36 and is fixed to a lever 40, which is connected by a link 41 to an arm 42 fast on the one end by a shaft 43 journaled in the main frame 1. The link 41 is connected at one end of the lever near the pawl, while the other end projects rearwardly and is pivoted at 44 to the oscillating arm 45 pivoted to the frame at 46. The lower end of the oscillating arm 45 is adjustably connected to the lay beam 2 by means of a bolt 47 which is arranged to engage a slot 48 in the lay beam and a slot 49 in the oscillating arm 45. Thus it will be seen that by reason of this bolt and slot connection between the oscillating arm 45 and lay beam 2, a proper movement may be given the pawl 39 and the rotation of the ratchet wheel 36 governed accordingly. The rocking movement of the lay beam 2 will impart a uniform movement to the pawl 39 and ratchet wheel 36, which in turn actuates the winding beam 23 through the pinion 38, spur gear 33 and pinion 34 fast on the winding beam 23, while the winding roll 28, at the same time, receives its motion through the pinion 32, fast on the spur gear 33, meshing with the spur gear 31 fixed on the roll. The pawl 39 is lifted out of engagement with the ratchet wheel 36, when desired, by means including an arm 50, secured to the other end of the shaft 43, which arm is connected by a link 50*, bell crank levers 51, 52 having links 53, 54, which link 54 is secured to one end of the usual angle lever 55, the movement of which is controlled by tubes and rolls (not shown) on the pattern chain 56. In conjunction with the pawl 39 a spring actuated pawl 57, pivoted to the main frame 1 at 58, is arranged to engage the ratchet wheel 36 and hold the same against unintentional movement. The pawl 57 is rocked out of engagement with the ratchet wheel 36 by means of a link 59 which connects the lever 40 with a tail 60 on the pawl 57. A flexible connection 61 leads from the other end of the angle lever 55 around suitable idler pulleys 62, 63 to one end of a bell crank lever 64 pivoted to the main frame 1 at 65. The other end of the bell crank lever 64 is provided with a flexible connection 66 which is guided in a pulley 67 adjustably mounted in a bracket 68 carried by the auxiliary frame 10. A weight 69 is attached to the end of the flexible connection 66 to apply a yielding tension to the parts connected therewith.

The arrangement of the pattern chain is

such that all of the heddles and their warp threads are used for weaving the body of the fabric between the plaits and only the heddles 6 and 7 and their warp threads are used for weaving the strip which is to form the plait, while the heddles 8 and 9 are held motionless.

The means employed for permitting the woven fabric to be drawn rearwardly at predetermined intervals for allowing the lay beam 2 to beat up the portion of the fabric which has been woven to form the plait is as follows:

A second pawl 70 is arranged to engage the ratchet wheel 36, which pawl is fixed to a lever 71, pivoted at 72 to the end of an arm 73 having its fulcrum at 74 on the main frame 1. This arm 73 is limited in its oscillatory movement by means of stops 75, 76, each of which is provided with a slot 77 and a bolt 78, which bolt secures its stop to the main frame 1. The pawl 70 on the lever 71 is yieldingly held in engagement with the ratchet wheel 36 by a spring 79 attached between a pin 80 on the main frame 1 and the lever 71. The pawl 70 is lifted out of engagement with the ratchet wheel 36 by means of a pin 81 projecting laterally from a rocking lever 82, one end of which is fulcrumed at 83 on the main frame 1, while the other end is attached to the usual angle lever 84 by a link 85. The movement of the angle lever 84 is also controlled by tubes and rolls (not shown) on the pattern chain 56.

The operation of my invention is as follows:—

All of the heddles 6 to 9 inclusive are operating alternately to form the body of the fabric being woven, and as the loom is operated, the finished fabric is wound onto the winding beam 23 in the manner hereinbefore set forth. After a predetermined amount of the body of the fabric has been woven the warp threads which lead from the beam 11 are held stationary and the warp threads which lead from the beam 12 are being utilized to weave the portion of the fabric which is to form the plait. When the desired amount of fabric to form the plait has been woven the winding mechanism is released and the fabric will be drawn rearwardly until the last shot of weft of the said plait is forced by the movement of the lay beam 2 into proximity to the first shot of weft of said plait, thereby forming a depending loop. While this beating up process is in operation all of the heddles have been set in motion, and the weaving of the body of the fabric is again begun. As the plait portion is being beaten up to form the plait, the regular shots of weft are introduced into the fabric, so that when the plait is finally set up there will be a sufficient number of shots of weft woven into the fabric to securely lock the plait.

The amount of fabric to be woven between each of the plaits is controlled by certain of the tubes and rolls on the pattern chain 56, and the size of the plait is controlled by other tubes and rolls on the pattern chain 56, which operates the angle levers 55 and 84, which levers are connected with the winding mechanism as has herebefore been set forth. The train of gear wheels of the winding mechanism is actuated by the oscillation of the lay beam 2 and the arm 45 which moves the lever 40 and with it the pawl 39, which in turn rotates the ratchet wheel 36 and the several gears in the train. This movement of the ratchet wheel 36 also carries the pawl 70 with its lever 71 and arm 73 rearwardly until the arm 73 rests against the stop 76. At this time, the pattern chain 56 will have been brought into position to actuate the angle lever 55, which movement, through the links 54, 53, bell crank levers 51, 52 link 50* and arm 50, will rock the shaft 43 with its arm 42, which in turn moves the lever 40 by the link 41 so as to lift the pawl 39 out of engagement with the ratchet wheel 36. Simultaneously with the movement of the lever 40, through the link 59, the pawl 57 will be thrown out of engagement with the ratchet wheel 36. When the ratchet wheel 36 is released of the pawls 39, 57, it will be free to move in a reverse direction and permit the woven fabric on the winding beam and roll to be drawn rearwardly by the tension of the weight 15 on the warp beam 11. This movement of the ratchet wheel 36 will also carry the pawl 70, lever 71 and arm 73 rearwardly until the arm 73 strikes the stop 75 and arrests the movement of the ratchet wheel, in which position the pawls 39 and 57 will be again brought into engagement with the ratchet wheel 36. The angle lever 84 is now actuated by the chain 56 and the lever 82 rocked through the link 85. This movement of the lever 82 brings the pin 81 in engagement with the lever 71 which is lifted so that the pawl 70 is disengaged from the ratchet wheel 36, after which the angle lever 84 is returned to its normal position and the pawl 70 caused to assume its engagement with the ratchet wheel 36. In this position, the arm 73 is substantially in contact with the stop 75, and as the fabric is woven and wound upon the winding beam 23 by the movement of the lay beam 2, arm 45, pawl 39, ratchet 36 and the adjacent mechanism, the arm 73 by reason of the pawl 70 engaging the ratchet wheel and lever 71 will be gradually carried rearwardly until it is arrested by the stop 76, at which time, the pattern chain 56 will again actuate the angle lever 55 and the sequence of operations by the various parts repeated. By reason of the mechanism above described, I am enabled to weave plaits of

varying width into the fabric during the continuous operation of the loom, and also weave plaits at various distances apart to suit different requirements.

The mechanism for inserting the weft in the fabric has been omitted from the drawings and description, since it would tend to unduly complicate the structure. Any suitable weft introducing means may be employed, as the structure which I have shown and described for weaving plaits into the fabric does not interfere with the weft introducing means.

What I claim is:—

1. In a loom, the combination with the frame, the lay beam, the winding beam, the winding roll, the gears and their shafts carried by the frame, said gears connecting said winding beam and roll, and the pattern chain, of a ratchet wheel coacting with said gears to control the movement of the winding beam, an arm pivoted to the frame and actuated by the lay beam, a fixed pawl carried by said arm arranged to engage said ratchet wheel for controlling the movement of the gears for winding the beam and roll, mechanism controlled by the pattern chain for releasing said pawl from the ratchet wheel, and a device engaging the ratchet wheel and having a limited movement therewith for predetermining the rearward movement of the winding beam.

2. In a loom, the combination with the frame, the lay beam, the winding beam, the winding roll, the gears and their shafts carried by the frame, said gears connecting said winding beam and roll, and the pattern chain, of a ratchet wheel coacting with said gears to control the movement of the winding beam, an arm pivoted to the frame and actuated by the lay beam, a fixed pawl carried by said arm arranged to engage said ratchet wheel for controlling the movement of the gears for winding the beam and roll, mechanism controlled by the pattern chain for releasing said pawl from the ratchet wheel, and an oscillating arm pivoted to the frame and provided with a pawl arranged to engage the ratchet wheel, said arm and pawl having a limited movement with the ratchet wheel for predetermining the rearward movement of the winding beam.

3. In a loom, the combination with the frame, the lay beam, the winding beam, the winding roll, the gears and their shafts carried by the frame, said gears connecting said winding beam and roll, and the pattern chain, of a ratchet wheel coacting with said gears to control the movement of the winding beam, an arm pivoted to the frame and actuated by the lay beam, a fixed pawl carried by said arm arranged to engage said ratchet wheel for controlling the movement of the gears for winding the beam and roll, mechanism controlled by the pattern chain

for releasing said pawl from the ratchet wheel, an oscillating arm pivoted to the frame, a lever pivoted to said arm provided with a pawl arranged to engage the ratchet wheel, said arm, lever and pawl having a limited movement with the ratchet wheel for predetermining the rearward movement of the winding beam.

4. In a loom, the combination with the frame, the lay beam, the winding beam, the winding roll, the gears and their shafts carried by the frame, said gears connecting said winding beam and roll, and the pattern chain, of a ratchet wheel coacting with said gears to control the movement of the winding beam, an arm pivoted to the frame and actuated by the lay beam, a pawl carried by said arm arranged to engage said ratchet wheel for controlling the movement of the gears for winding the beam and roll, mechanism controlled by the pattern chain for releasing said pawl from the ratchet wheel, and a device engaging the ratchet wheel for predetermining the rearward movement of the winding beam, said device comprising an oscillating arm pivoted to the frame, a lever pivoted to said arm, a pawl carried by said lever, and stops arranged to be engaged by said arm.

5. In a loom, the combination with the frame, the lay beam, the winding beam, the winding roll, the gears and their shafts carried by the frame, said gears connecting said winding beam and roll, and the pattern chain, of a ratchet wheel coacting with said gears to control the movement of the winding beam, an arm pivoted to the frame and actuated by the lay beam, a pawl carried by said arm arranged to engage said ratchet wheel for controlling the movement of the gears for winding the beam and roll, mechanism controlled by the pattern chain for releasing said pawl from the ratchet wheel, and a device engaging the ratchet wheel for predetermining the rearward movement of the winding beam, said device comprising an oscillating arm pivoted to the frame, a lever pivoted to said arm, a pawl carried by said lever, and adjustable stops secured to the frame and arranged to be engaged by said arm.

6. In a loom, the combination with the frame, the lay beam, the winding beam, the winding roll, the gears and their shafts carried by the frame, said gears connecting said winding beam and roll, and the pattern chain, of a ratchet wheel coacting with said gears to control the movement of the winding beam, an arm pivoted to the frame and actuated by the lay beam, a pawl carried by said arm arranged to engage said ratchet wheel for controlling the movement of the gears for winding the beam and roll, mechanism controlled by the pattern chain for releasing said pawl from the ratchet wheel, and a device engaging the ratchet wheel for predetermining the rearward movement of the winding beam, said device comprising an oscillating arm pivoted to the frame, a lever pivoted to said arm, a pawl carried by said lever, adjustable stops secured to the frame and arranged to be engaged by said arm, and means for releasing said last named pawl from the ratchet wheel.

7. In a loom, the combination with the frame, the lay beam, the winding beam, the winding roll, the gears and their shafts carried by the frame, said gears connecting said winding beam and roll, and the pattern chain, of a ratchet wheel coacting with said gears to control the movement of the winding beam, an arm pivoted to the frame and actuated by the lay beam, a pawl carried by said arm arranged to engage said ratchet wheel for controlling the movement of the gears for winding the beam and roll, mechanism controlled by the pattern chain for releasing said pawl from the ratchet wheel, and a device engaging the ratchet wheel for predetermining the rearward movement of the winding beam, said device comprising an oscillating arm pivoted to the frame, a lever pivoted to said arm, a pawl carried by said lever, and adjustable stops secured to the frame and arranged to be engaged by said arm, and means for releasing said last named pawl from the ratchet wheel, said means being controlled by the pattern chain.

In testimony, that I claim the foregoing as my invention, I have signed my name this fifth day of December, A. D. 1924.

WILLIAM J. LUTTON.
